UNITED STATES PATENT OFFICE.

JULIUS SCHMOHL AND ERNST LAUSCHKE, OF CHICAGO, ILLINOIS, ASSIGNORS
TO BARNHART BROTHERS & SPINDLER, OF SAME PLACE.

DESIGN FOR A FONT OF PRINTING-TYPE.

SPECIFICATION forming part of Design No. 20,516, dated February 10, 1891.

Application filed December 31, 1890. Serial No. 376,407. Term of patent 14 years.

To all whom it may concern:

Be it known that we, JULIUS SCHMOHL and ERNST LAUSCHKE, subjects of the Emperor of Germany, residing at Chicago, county of Cook, 5 and State of Illinois, have invented and produced a new and original Design for a Font of Printing-Type, which is fully set forth in the following specification, reference being had to the accompanying typographical im- 10 pressions, forming a part thereof.

This design comprises upper and lower case letters, points, figures, character &, and dollar-mark. It is in general style much condensed, especially the lower-case letters. A 15 distinguishing characteristic is the erratic shading of the lower-case letters—that is to say, the absence of uniformity of method in applying shades. Thus lower-case h, k, l, m, n, and u are without shades. Lower-case i, 20 j, l, r, and t may also be added to this list; but as these letters consist of but a single stroke the absence of shades is not marked. Lower-case b, d, p, and q have their corresponding oval elements lightened at the middle with the shades at the upper and lower 25 ends, while the oval elements of lower-case g and o have swell shades merging in fine lines toward both ends substantially alike, while the oval elements of lower-case a, c, and e 30 have the swell shades tapering gradually to

fine lines at the top and abruptly at points at the bottom—that is, the shade is what might be termed a “drooping” shade, the weight being accumulated toward the lower end. Lower-case v, w, x, y, and z have their 35 lines alternately heavy and light. There are thus presented in the lower-case letters four different modes of applying shades, the second of which, presented in letters b, d, p, and q, is quite peculiar and strongly in contrast 40 with the mode of shading presented in letters g and o. In like manner the mode of shading, or rather the absence of shades, in letters h, i, j, k, l, m, and t is in marked contrast 45 with the alternately light and heavy lines of letters v, w, x, y, and z.

We claim—

The design for a font of type herein shown and described, wherein the lower-case letters are much condensed and erratically shaded, 50 substantially as set forth.

In testimony whereof we have hereunto set our hands, at Chicago, Illinois, this 18th day of December, 1890.

JUL. SCHMOHL.
ERNST LAUSCHKE.
